COMPOSITE, SELF-WATERING PLANT RECEPTACLE

Jan Berglund, Mulljo, Sweden, assignor to
Sinnjet AB, Huskvarna, Sweden

Filed Oct. 7, 1974, Ser. No. 512,950

Term of patent 14 years

Int. Cl. D11—02

U.S. Cl. D11—156

FIG. 1

FIG. 3

FIG. 5

FIG. 6

FIG. 1 is a perspective view of a composite, self-watering plant receptacle showing my new design;

FIG. 2 is a perspective view of the soil insert member, shown separately for clarity of illustration;

FIG. 3 is a side elevation thereof;

FIG. 4 is a perspective view of the water supply tube;

FIG. 5 is a perspective view of the water reservoir base member; and

FIG. 6 is a side elevation thereof.

I claim:

The ornamental design for a composite, self-watering plant receptacle, substantially as shown and described.
